REVERSIBLE OUTER GARMENT

John T. Callahan, West Newton, and John Arthur Gilbertson, Milford, Mass., assignors to Archer Rubber Company, Milford, Mass., a corporation of Massachusetts

Application March 8, 1943, Serial No. 473,336

10 Claims. (Cl. 2—93)

This invention pertains to waterproof or water-repellent outer garments, more especially to garments of the type disclosed in our copending application for Letters Patent Serial No. 473,074, filed January 21, 1943. The sleeved garment described in said application is so designed as to furnish adequate ventilation while dispensing with the usual exposed shoulder seams, and consists of but four pieces of material (excluding the collar and trim). Thus, the body of the coat comprises a unitary yoke member with which the sleeves are integral and whose rear portion forms a freely swinging flap or cape; a back member whose upper portion extends upwardly beneath said loose flap or cape and whose upper end is permanently secured to the collar; and two side members.

The principal object of the present invention is to provide a sleeved garment embodying all of the desirable features and advantages disclosed in the aforesaid application but which is reversible so that it may be worn either side out at will and without sacrifice of its water-repellent function or adequacy of ventilation when worn in either way and which is of substantially the same structural design when worn either side out. Such reversibility is often desirable, for example, to permit the alternative exposure of surfaces of different finishes, for instance, smooth or rough; or when the garment is to be used in the military service to permit alternative exposure of surfaces of different colors or patterns, for instance, for camouflage purposes.

Other and further objects and advantages of the invention will be pointed out in the following more detailed description and by reference to the accompanying drawing wherein:

Fig. 1 is a diagrammatic perspective view of the complete garment showing its front portion;

Fig. 2 is a similar view of the rear of the garment;

Fig. 3 is a view similar to Fig. 2 but showing the garment as having been turned inside out;

Fig. 4 is a fragmentary rear elevation of the upper part of the garment with certain parts broken away to show the interior construction;

Fig. 5 is a view generally similar to Fig. 4 but showing the garment prepared for reversal;

Fig. 6 is a fragmentary section, to larger scale, substantially on the line 6—6 of Fig. 4;

Fig. 7 is a fragmentary section, to larger scale, on the line 7—7 of Fig. 4;

Fig. 8 is a diagrammatic plan view to small scale illustrating a blank useful in making the yoke portion of the garment; and

Fig. 9 is a similar view of a blank useful in forming the back member of the garment.

Referring to the drawing, the numeral 1 designates the completed garment which is here shown in a diagrammatic way and without attempt to illustrate the natural draping of the fabric or usual or minor details of construction. This garment, except for the collar 2 and customary elements of trim, for example pockets and pocket-stays, button and button-fly, facings and similar reinforcements, consists solely of four pieces of material, to wit, the yoke member 7, the back member 14 and the two front members 5 and 6. The yoke member 7 (Fig. 8) consists of a single integral piece of material. This material is of any desired character useful in making the intended type of garment; for instance, if the garment is to be of waterproof or water-repellent type, the material may be a textile fabric impregnated, sprayed or coated with a water-resistant or water-repellent medium, for instance, rubber or rubber compound, if available, or one of the synthetic resins or rubber substitutes, oxidized oil, or in fact any other suitable material.

When, in accordance with the present invention, the garment is to be made reversible, the material employed will preferably be of different surface appearance or character at its opposite sides. For instance, one surface may be smooth and the other may be rough; one surface may be white and the other black, or if the garment be employed for military use and intended for camouflage, the opposite surfaces may have different protective colorings or patterns, for example, to imitate green foliage, and dry and brown foliage, respectively. Herein, for ease of description, the surface appearance designated A (Fig. 2) will be referred to as the outer surface, and the surface appearance designated B (Fig. 3) will be referred to as the inner surface, with the understanding that in accordance with the manner in which the garment is worn either of these surfaces may be exposed at its exterior.

The yoke member 7 has a central or shoulder portion having at its forward part a neck opening 8 (Fig. 8) bounded by a curved edge 9 which intersects forwardly divergent straight edges which, in the completed garment, constitute upper portions of the front closure. This yoke also comprises integral portions 10 and 11 designed to form the sleeves of the garment, and also comprises the portion 12 which, in the completed garment, forms a cape-like flap which hangs down and is disposed to the rear of the upper portion of the back member of the garment, its lower

edge 13 being free from the back member except at its opposite ends.

The back member 14 (Fig. 9) is also a single, integral piece of material comprising a substantially rectangular lower portion and an upper portion 15 which is of more or less truncated triangular shape, tapering upwardly and having the inclined convergent edges 16 and 17 and the upper edge 18. The lower edge 15 of this back member is finished, for example, by hemming, and defines the lower edge of the rear part of the garment.

The upper edges of the front members 5 and 6 are secured to the yoke member by seams S (Fig. 1) which may be stitched or cemented or combinations of stitching and cementing, the seam S being substantially in the horizontal plane of the armpit P (Fig. 4). The rear edges of the front members 5 and 6 are united to the forward, substantially vertical side edges of the back member 14 by the side seams K. The portion 12 of the yoke is of such vertical depth that it depends below the plane of the points P, its lower edge 13 being at a substantial distance, for example 6", below the horizontal plane of the points P. At the points X (at which the edge 13 meets the seams K), the yoke is permanently united both to the back 14 and to the respective front members 5 and 6, but above the points X the lateral edges of the back 14 are not caught into the side seams K, the latter merely uniting the front members 5 and 6 to the respective lateral edges of the yoke from the points X to the points P. Above the horizontal plane of the points X, there is no permanent connection between the portion 15 of the back member and the yoke member 7, the edges 16 and 17 of the back member always being free from the yoke member and thus providing slits or openings of large area leading from the interior of the garment into the space between the central portion of part 15 of the back member and the depending cape-like flap 12 of the yoke member.

The upper portion of the part 15 of the back member, adjacent to its edge 18, is provided at each of its opposite corners (Fig. 5) with a pair of snap fastener members 19 and 20, respectively, the two fasteners 19 and 20 of each pair being oppositely arranged. Thus, assuming that these elements 19 and 20 are the female elements of the fastener, the socket of the member 20 (Fig. 6) may be directed toward the interior of the garment, while the socket of the fastener 19 is directed toward the exterior of the garment.

The yoke member 7 (Figs. 6 and 8) is similarly provided adjacent to its collar line or edge 9 with the complementary elements of the snap fasteners, such elements being arranged in pairs and indicated at 21 and 22, respectively. The male elements 21 and 22, constituting each of the pairs, are also arranged respectively to face in opposite directions. The fasteners constitute releasable means for connecting the upper end of the part 15 to the yoke member. By this arrangement of oppositely facing fastener elements, it is possible, for example, to connect the part 15 to the part 7 so that the inner surface B of the part 7 is opposed to the outer surface A of the part 15, or, alternatively, so that the inner surface B of the part 15 is opposed to the outer surface A of the part 7.

The part 15 of the back member is also preferably furnished at points located intermediate the points X and P (Figs. 4 and 9), with buttonholes 23, and the yoke member 7 is furnished

with buttons 24 (Figs. 4, 5 and 8) designed to engage the buttonholes 23 and with the latter constituting separable fasteners for uniting the yoke and back member. The buttons 24 are arranged in pairs, one button 24 of each pair being disposed at the inside of the yoke member (Fig. 7), and the other button 24 disposed at the outside of the yoke member.

Assuming that the garment is arranged as shown in Figs. 2 and 4 with the surface A at the outside, and with the upper portion 15 of the back member extending up beneath the cape 12, and further assuming that the snap fasteners 19, 21 are engaged thereby to unite the upper end of the part 15 with the yoke member at the collar line, and further assuming that the buttons 24 are engaged in the buttonholes 23, it will be noted that the edges 16 and 17 of the member 15 are free from the yoke member, thus providing the desired ventilation, and that the lower edge 13 of the cape member extends well below the lower ends of the ventilating slits so that there is no danger that water will enter to the interior of the garment through these slits. If now it be desired for any reason to have the opposite surface B of the garment exposed at the outside, the first step is to disconnect the fasteners 19, 21 and to release the buttons 24 from the buttonholes 23. Preferably, the portion 15 of the back member is now pulled down from beneath the cape and drawn up over the outside of the cape, as indicated in Fig. 5, whereupon the fasteners 20, 22 are engaged and the other button of each pair of buttons 24 is engaged with the corresponding buttonhole 23. With the parts in this position, the garment is turned inside out, the sleeves being turned during this operation, with the result that when the turning operation has been completed, the garment has the appearance shown in Fig. 3 wherein the portion 15 of the back member again lies beneath and is substantially concealed by the cape portion 12 of the garment, and with the same arrangement of ventilating slits, although now the surface B of the garment is externally exposed throughout the entire area of the garment.

As thus designed, it is readily possible for the wearer to turn the garment inside out while retaining the desired waterproof characteristics and ventilating capabilities, and without substantial change in the structural appearance of the garment, and in doing so all that is necessary, in addition to the mere turning of the garment, is to unbutton the portion 15 of the rear member, draw it down and then upwardly over the cape portion 12 and re-fasten it before turning the garment.

While snap fasteners, buttons and buttonholes have been indicated as desirable types of releasable fasteners, it is to be understood that any other suitable means may be employed, and further that any and all variations in structural details and arrangement of parts which fall within the terms of the appended claims are to be regarded as within the scope of the invention.

We claim:

1. A reversible garment made of material whose opposite surfaces are different, said garment comprising a single-ply back member, a pair of front members, means permanently uniting the rear edges of the front members to the opposite edges respectively of the back member from the arm pits substantially to the lower edge of the garment, the back member reaching up to the collar line, and a one-piece yoke comprising a

part constituting a cape-like flap disposed to the rear of the back member, the like surfaces of the back and cape-like flap being concomitantly exposed at the exterior of the garment, said flap being free from connection to the back member except at points adjacent to the respective arm scyes and releasable uniting means, said uniting means being so constructed and arranged that, regardless of which surface of the garment is externally exposed, the cape-like flap may always be disposed to the rear of the back member.

2. A reversible garment made of material whose opposite surfaces are different, said garment comprising a yoke member with which each sleeve is integral a pair of front members, and a one-piece back member, means permanently uniting the rear edges of the front member to the opposite edges respectively of the back member from the arm pits substantially to the lower edge of the garment, the upper portion of the back member extending upwardly within the yoke member but which is free from the yoke member from the collar line to points below each arm-pit portion thereby providing free ventilation for the upper portion of the garment, the rear part of the yoke member forming a depending cape-like flap normally disposed to the rear of the back member, the lower portion of said flap being entirely free from the back member from a point adjacent to one arm scye to a point adjacent to the other arm scye, the like surfaces of the back and cape-like flap being concomitantly exposed to the exterior of the garment, and releasable fastener means, said fastener means being so constructed and arranged that, regardless of which surface of the garment is externally exposed, the upper end of the back member may be secured to the yoke member with the cape-like flap always disposed rearwardly of the back member.

3. A reversible garment made of material whose opposite surfaces are different, said garment comprising two front members, a one-piece yoke member with which each sleeve is integral and a single-ply back member which extends upwardly within the yoke member but which is free from the yoke member from the collar line to points below each arm-pit portion thereby providing free ventilation for the upper portion of the garment, means permanently uniting the rear edges of the respective front edges to the opposite edges of the back member from the arm pits downwardly substantially to the lower edge of the garment, the rear part of the yoke member forming a depending cape-like flap normally disposed to the rear of the upper portion of the back member, the like surfaces of the back and cape-like flap being concomitantly exposed to the exterior of the garment, the lower portion of said flap being free from the back member from adjacent to one arm scye to adjacent to the other arm scye, the upper end of the back member and the collar portion of the yoke member having complementary elements respectively of separable fasteners exposed at their opposite surfaces so that, regardless of the surface of the garment which may be externally exposed, the cape-like flap may always be disposed rearwardly of the back member.

4. A reversible garment made of material 70 whose opposite surfaces are different, said garment comprising a yoke member with which each sleeve is integral and a back member which extends upwardly within the yoke member but which is free from the yoke member from the

collar line to points below each arm-pit portion thereof providing free ventilation for the upper portion of the garment, the rear part of the yoke member forming a depending cape-like flap normally disposed to the rear of the back member, the like surfaces of the back and cape-like flap being concomitantly exposed to the exterior of the garment, the upper end of the back member and the collar portion of the yoke member having complementary elements, respectively, of separable fasteners exposed at their opposite surfaces, and the lateral edges of the back member and yoke member also having complementary elements, respectively, of separable fasteners exposed at their opposite surfaces at points below the respective arm-pit portions but above the lower edge of the cape-like flap so that regardless of the surface of the garment which may be externally exposed the cape-like flap may be always disposed rearwardly of the back member.

5. A reversible garment whose inner and outer surfaces are different, said garment having full length sleeves and a body portion, the garment comprising a yoke member with which each entire sleeve is integral, a back member, and two front members, the back member extending upwardly within the rear portion of the yoke member but being free from the yoke member except at the collar line and at points immediately adjacent to each arm-pit portion thereby providing free ventilation for the upper portion of the garment, means releasably uniting the upper end of the back member to the yoke member at the collar line, and means releasably uniting the yoke member and the back member at points below each arm-pit portion.

6. A reversible garment whose inner and outer surfaces are different, said garment having full length sleeves and a body portion, the garment comprising a yoke member with which each entire sleeve is integral, a back member, and two front members, the back member extending upwardly within the rear portion of the yoke member but being free from the yoke member except at the collar line and at points immediately adjacent to each arm-pit portion thereby providing free ventilation for the upper portion of the garment, the upper edge portion of the back member having at both its inner and outer sides, respectively, one element of a separable fastener, and the yoke member having at both its inner and outer sides respectively, adjacent to the collar line, the complementary fastener elements whereby the upper end of the back member may be releasably united to the yoke adjacent to the collar line with the inner surface contacting the outer surface of the yoke or alternatively with the outer surface of the back contacting the inner surface of the yoke.

7. A reversible, waterproof, outer garment whose opposite sides are different, said garment having full length sleeves and a body portion and comprising a yoke member with which each entire sleeve is integral, a back member and two front members, the back member extending upwardly within the yoke member, the yoke being seamed to each front member along a line substantially in the plane of the arm-pits, the lower edge of the rear portion of the yoke member being at a substantial distance below the plane of the arm-pits, said lower edge being free from the back member across its entire width but being permanently united to the back at points spaced below the respective arm-pits, means operative releasably to unite the back member to

the yoke at points spaced above each of said points of permanent union, and means operative releasably to unite the upper edge of the back member to the yoke adjacent to the collar line.

8. A reversible, waterproof, outer garment whose opposite sides are different, said garment having full length sleeves and a body portion and comprising a yoke member with which each entire sleeve is integral, a back member and two front members, the back member extending upwardly within the yoke member, the yoke being seamed to each front member along a line substantially in the plane of the arm-pits, the lower edge of the rear portion of the yoke member being at a substantial distance below the plane of the arm-pits, said lower edge being free from the back member across its entire width but being permanently united to the back at points spaced below the respective arm-pits, the back member extending upwardly beneath the rear portion of the yoke member, the upper edge of the back member having one element of a separable fastener and the yoke member having the complementary element of said fastener located at a point adjacent to the collar line whereby the upper portion of the back member may be detachably united to the yoke member.

9. A reversible, waterproof, outer garment whose opposite sides are different and which has full length sleeves and a body portion, the garment comprising a yoke member with which each entire sleeve is integral, a back member and two front members, the back member extending upwardly within the yoke member, and the yoke member being seamed to each front member along a line substantially in the plane of the arm-

pits, the rear portion of the yoke member forming a cape-like flap whose lower edge is free from the back member except at points spaced below the respective arm-pits, means permanently uniting the yoke and back at said latter points, means releasably uniting the yoke and back above said points of permanent union but below the respective arm-pits, and means releasably uniting the upper end of the back member to the yoke adjacent to the collar line.

10. A reversible, waterproof, outer garment whose opposite sides are different and which has full length sleeves and a body portion, the garment comprising a yoke member with which each entire sleeve is integral, a back member and two front members, the back member extending upwardly within the yoke member, and the yoke member being seamed to each front member along a line substantially in the plane of the arm-pits, the rear portion of the yoke member forming a cape-like flap whose lower edge is free from the back member except at points below the respective arm-pits, means permanently uniting said lower edge portion of the yoke to the back member at said points, the yoke member having one element of a separable fastener disposed above each of said points of permanent union but below the respective arm-pits, and the back member having at its opposite sides respectively complementary elements of said separable fastener whereby the opposite sides of the back member may be releasably attached to the yoke member at points above the lower edge of the cape-like flap.
